United States Patent Office

Des. 220,348
Patented Mar. 30, 1971

220,348

TOY FIGURE

John B. McCorkle, 442 Bristol St.,
Brooklyn, N.Y. 11212

Filed Oct. 15, 1969, Ser. No. 19,570

Term of patent 14 years

Int. Cl. D21—02

U.S. Cl. D34—2

Fig. 1.

Fig. 2.

Fig. 3.

Fig. 4.

FIG. 1 is a front elevational view of a toy figure embodying my new design;

FIG. 2 is a side elevational view of the toy figure;

FIG. 3 is a top plan view of the toy figure; and

FIG. 4 is a back elevational view of the toy figure.

I claim:

The ornamental design for a toy figure, substantially as shown.
